LACE

Sam Women Sam, Chicago, Ill.

Application December 27, 1950, Serial No. 202,905

4 Claims. (Cl. 24—143)

1

My invention relates to laces, particularly, of the elastic rubber type of individual shoe laces for each pair of opposite eyelets of a shoe. This application is a continuation-in-part of my former application titled "Lace" Serial Number 10,826, filed February 25, 1948, which former application I abandoned in favor of the instant application Serial Number 202,905, filed December 7, 1950.

The chief object is to make such type of shoe laces practicable.

Another object is to devise such a shoe lace whose flanged integral ends are, at first, conveniently drawable through the eyelets of a shoe and, finally, when the flanged ends are in anchorable position in relation to the eyelets of a shoe, the flanged ends are provided with conveniently applicable means to render the flanged ends not redrawable through the same eyelets during normal use.

Other objects and advantages become apparent as the description proceeds.

I attain these objects by devices illustrated in the accompanying drawing, in which—

Figure 1 is a longitudinal sectional view of one form of the assembled shoe lace;

Figure 2 is a longitudinal sectional view of the principal member forming part of the same form of the shoe lace;

Figure 3 is an end view of the same form of the assembled shoe lace;

Figure 4 is an end view of the same form of the assembled shoe lace but differing from it in that the circular aperture 7 is substituted for the narrow slit aperture 1;

Figure 5 is an end view of the same principal member;

Figure 6 is a front view of the disk reinforcing member 3;

Figure 7 is a side view of the same disk reinforcing member 3;

Figure 8 is a longitudinal sectional view of an alternative form of the assembled shoe lace;

Figure 9 is an end view of the same form of the assembled shoe lace;

Figure 10 is a front view of the annular reinforcing member 10;

Figure 11 is an axial sectional view of the annular reinforcing member 10;

Figure 12 is a longitudinal sectional view of the principal member forming part of the alternative form of the shoe lace;

Figure 13 is an end view of the same principal member;

2

Figure 14 is a longitudinal sectional view of a third form of the assembled shoe lace;

Figure 15 is a longitudinal sectional view of the principal member forming part of the third form of the shoe lace but varied by having a different number and locations of the slit apertures.

Figure 16 is a longitudinal sectional view of a fourth form of the assembled shoe lace;

Figure 17 is an end view of the fourth form of the assembled shoe lace;

Figure 18 is a bottom view of the third form of the assembled shoe lace;

Figure 19 is a bottom view of the principal member forming part of the third form of the shoe lace;

Figure 20 is a longitudinal sectional view of the principal member forming part of the fourth form of the shoe lace;

Figure 21 is an end view of the principal member forming part of the fourth form of the shoe lace;

Figure 22 is a side view of the spherical reinforcing member 19;

Figure 23 is a front view of the spherical reinforcing member 19;

Figure 24 is a side view of the separate elastic tubular member 5;

Figure 25 is a front view of tubular member 5;

Figure 26 is an axial sectional view of the split ring reinforcing member 15; and

Figure 27 is a front view of the split ring reinforcing member 15.

The shoe lace indicated in Figures 1 to 7 and 24 and 25 comprises a slender cylindrical intermediate supple elastic string member 4 which spans across from an eyelet to an opposite eyelet of a shoe and also comprises a pair of integral, thin, flat, disk-shaped, supple, stretchable and hollow elastic members 2. Each hollow

elastic member 2 is closed at its inner face and integrally connected at its inner face to each end of elastic string member 4 and comprises a very narrow slit aperture 1 at the outer face which leads into disk-shaped hollow 6 of the

hollow elastic member 2. The shoe lace also comprises a thin, flat, disk-shaped, preferably but not necessarily resilient reinforcing member 3 whose rim is rounded semi-circularly from face to face, whose entire surface is smooth and which

fits snugly in hollow 6. Hollow elastic member 2 is adapted to be stretched out of normal shape to receive reinforcing member 3 through slit aperture 1 and to hold reinforcing member 3 when the hollow elastic member 2 has resumed its

normal shape. Hollow elastic member 2, when

containing reinforcing member 3, being adapted to act as a stop to prevent removal of the shoe lace through a shoe eyelet. The shoe lace also comprises a separate elastic tubular member 5 having a central hole 21. Tubular member 5 has an external diameter slightly greater than the internal diameter of a shoe eyelet and whose internal diameter is slightly less than the diameter of the elastic string member 4, so as to have a tight frictional engagement therewith. Tubular member 5 has an axial length substantially the same as that of a shoe eyelet and is located in contact with hollow elastic member 2 and is adapted to fit snugly in a shoe eyelet.

The alternative form of the shoe lace indicated in Figures 8 to 13 also comprises a slender cylindrical intermediate supple elastic string member 4 which spans across from an eyelet to an opposite eyelet of a shoe and also comprises a pair of integral, thin, flat, disk-shaped, supple, stretchable and hollow elastic members 8. Each hollow elastic member 8 is closed at its outer face and integrally connected at its outer face to each end of elastic string member 4 and comprises an annular, very narrow slit aperture 9 at the inner face which leads into the annular hollow 12 of the hollow elastic member 8. The shoe lace also comprises a thin, flat, circular, annular, resilient reenforcing member 10, having a central hole 11 to engage elastic string member 4, whose rim and hole edge are rounded semi-circularly from face to face, whose entire surface is smooth and which fits snugly in hollow 12. Hollow elastic member 8 is adapted to be stretched out of normal shape to receive annular reenforcing member 10 through the annular slit aperture 9 and to hold annular reenforcing member 10 when the hollow elastic member 8 has resumed its normal shape. Hollow elastic member 8, when containing annular reenforcing member 10, being adapted to act as a stop to prevent removal of the shoe lace through a shoe eyelet.

The third form of the shoe lace is indicated in Figures 14, 15, 18, 19, 26 and 27 and comprises a wide, thin, flat, supple, elastic string member 13 which spans across from an eyelet to an opposite eyelet of a shoe and also comprises a pair of integral, thin, flat, disk-shaped, supple, stretchable and hollow elastic members 16. Each hollow elastic member 16 is integrally connected at both faces to an elastic link 14. Links 14 are integrally connected to elastic string member 13. The axial length of elastic links 14 is less than that of an eyelet of a shoe. The width of the wide elastic string member 13 is sufficient to enable each upper elastic string member 13 to overlap each next lower elastic string member 13 like the shingles of a roof and thus are enabled to shed rain like the shingles of a roof. Each hollow elastic member 16 is indirectly integrally connected at both faces to each end of elastic string member 13 by way of an elastic link 14. One hollow elastic member 16 has two slit apertures 24 and 25, one at each face which lead into the hollow 17 of the hollow elastic member 16. The other has one slit aperture 26 at its outer face. Each hollow elastic member 16 in Figure 15 has one slit aperture 27. One has a slit aperture 1 at its outer face, the other has a slit aperture 28 at its inner face. The purpose of the variation in number and position of the slit apertures as illustrated and described is to indicate some of the possible scope of variation in respect to apertures and other features of the shoe lace. This shoe lace also comprises a thin, flat, circular, annular, resilient split ring reen-

forcing member 15 having a central hole 22 to engage link 14 and split 23 and whose rim and hole edge are rounded semi-circularly from face to face, whose entire surface is smooth and which fits snugly in hollow 17. Hollow elastic member 16 is adapted to be stretched out of normal shape to receive split ring reenforcing member 15 through slit aperture 1 and to hold split ring reenforcing member 15 when hollow elastic 16 has resumed its normal shape. Hollow elastic member 16, when containing split ring reenforcing member 15, being adapted to act as a stop to prevent removal of the shoe lace through a shoe eyelet. The opposed straight edges of the split 23 of split ring reenforcing member 15 are moved apart and one edge is inserted in split aperture 1 of hollow elastic member 16 and then split ring reenforcing member 15 is rotated to insert it in annular hollow 17 of hollow elastic member 16.

The fourth form of the shoe lace indicated in Figures 16, 17, 20, 21, 22 and 23 comprises a slender cylindrical intermediate supple elastic string member 4 which spans across from an eyelet to an opposite eyelet of a shoe and also comprises a pair of integral, spherical, supple, stretchable and hollow elastic members 18. Each hollow elastic member 18 is closed at its inner face and integrally connected at its inner face to each end of the elastic string member 4 and comprises a circular aperture 7 at the outer face which leads into spherical hollow 20 of the hollow elastic member 18. The shoe lace also comprises a spherical, thick, rigid reenforcing member 19 whose entire surface is smooth and whose corners are rounded and which fits snugly in hollow 20. Hollow elastic member 18 is adapted to be stretched out of normal shape to receive reenforcing member 19 through circular aperture 7 and to hold reenforcing member 19 when the hollow elastic member 18 has resumed its normal shape. Hollow elastic member 18, when containing reenforcing member 19, being adapted to act as a stop to prevent removal of the shoe lace through a shoe eyelet. The hollow elastic member 18 holding reenforcing members 19 are intended to be located at the outer sides of shoe eyelets.

The various forms of the lace may be also used to lace together cuffs and may be used as a front and rear collar button and may be used as a holder of keys. Other uses are also conceivable.

I claim:

1. A shoe lace comprising a flexible and elastic string member, a pair of hollow elastic members each integrally connected to each end of said elastic string member and each having an aperture at a face, and a pair of reenforcing members, each said hollow elastic member being adapted to be stretched out of normal shape to receive each said reenforcing member through each said aperture and to hold each said reenforcing member when each said hollow elastic member has resumed its normal shape, each said hollow elastic member when containing each said reenforcing member being adapted to act as a stop to prevent removal of said shoe lace through a shoe eyelet.

2. Adapted for use as the principal component of a shoe lace as set forth in claim 1, in combination, a flexible and elastic string member and a pair of hollow elastic members each integrally connected to each end of said elastic string member and each having an aperture at a face; each said hollow elastic member being adapted

to be stretched out of normal shape to receive a reinforcing component through each said aperture and to hold a said reenforcing component when each said hollow elastic member has resumed its normal shape, each said hollow elastic member when containing a said reenforcing component being adapted to act as a stop to prevent removal of said shoe lace through a shoe eyelet.

3. A shoe lace comprising a flexible and elastic string member, a flange integrally connected to one end of said elastic string member, means to prevent said flange from passing through a shoe eyelet during normal operation, said flange together with said means being thin and flat, a hollow elastic member integrally connected to the other end of said elastic string member and having an aperture at a face, and a reenforcing member, said hollow elastic member being adapted to be stretched out of normal shape to receive said reenforcing member through said aperture and to hold said reenforcing member when the said hollow elastic member has resumed its normal shape, said hollow elastic member, when containing said reenforcing member, being adapted to act as a stop to prevent removal of the shoe lace through a shoe eyelet, said hollow elastic member while holding said reenforcing member being thin and flat during normal operation.

4. Adapted for use as the principal component of a shoe lace as set forth in claim 3, in combina- 30

tion, a flexible and elastic string member, a flange integrally connected to one end of said elastic string member, means to prevent said flange from passing through a shoe eyelet during normal operation, said flange together with said means being thin and flat, a hollow elastic member integrally connected to the other end of said hollow elastic string member and having an aperture at a face; said hollow elastic member being adapted to be stretched out of normal shape to receive a reenforcing component through said aperture and to hold said reenforcing component when said hollow elastic member has resumed its normal shape, said hollow elastic member, when containing said reenforcing component, being adapted to act as a stop to prevent removal of said shoe lace through a shoe eyelet, said hollow elastic member while holding said reenforcing component being thin and flat during normal operation.
